COP WINDING MACHINE

Walter Siegenthaler, Erlenbach, Zurich, Switzerland, assignor to the firm Maschinenfabrik Schärer, Erlenbach, Zurich, Switzerland

Application June 3, 1941, Serial No. 396,463
In Switzerland June 5, 1940

7 Claims. (Cl. 242—27)

This invention relates to cop winding machines comprising the combination of thread guide means with feed means and winding feeler means which latter means are intermittently advanced on a guide spindle by action of the feed means in dependence of the working operation by means of a screw bore, the guide spindle being provided with screw threads only on a portion of its circumference and the winding feeler means cooperating toward the end of its traverse with a stop member arranged on the guide spindle, whereby the guide spindle is so rocked with the aid of additional means that the winding feeler means comes to bear on the portion of the circumference of the guide spindle devoid of screw threads in order to be slidingly returned on said spindle, whereupon, due to cooperation of the winding feeler means with a second stop member provided on the guide spindle the latter is rocked back into the initial position, thereby moving the screw bore of the winding feeler means into engagement with the screw thread of the guide spindle again.

By means of this arrangement the operation of the feed device is simplified in reliable manner.

The cop winding machine according to the invention is illustrated in the accompanying drawings by way of example only, in which

Fig. 1 shows an elevation of this embodiment of the invention in which the thread guide is removed from a conical winding feeler member;

Fig. 2 is a top plan view of Fig. 1;

Fig. 3 is an end view partly in section;

Fig. 4 is a view of means for rocking the guide spindle on a larger scale;

Fig. 5 shows a cross-section on the line V—V in Fig. 4;

Fig. 6 illustrates a clamping mechanism partly in axial section;

Fig. 7 is a cross-section on the line VII—VII in Fig. 6;

Fig. 8 is an axial section of the winding feeler means;

Fig. 9 is an elevational view;

Fig. 10 is a similar view with parts in displaced positions compared with Fig. 9;

Fig. 11 is a top plan view of Fig. 10;

Fig. 12 is an elevational view with parts in displaced positions compared with Figs. 9 and 10, and

Fig. 13 is a top plan view of Fig. 12.

The thread guide carrier rod 1 is longitudinally reciprocated during the cop building operation by a driving gearing arranged in a box 35 and 55

comprising a cam member 36 (Fig. 2), and by a driving member 38 which is controlled by a circumferential groove 37 of said member. The end of the thread guide carrier rod 1 remote from the gear box 35 is located in a mounting member 2 which is firmly connected to the gear box 35 by means of a supporting bar 39.

As shown in Figs. 6 and 7, on the thread guide carrier rod 1 is mounted a sleeve 3 to which a carrier arm 5 for the thread guide 6 is secured by means of two screw nuts 4. On one of the nuts 4 abuts a coil spring 7 which acts on a locking sleeve 8 which is slid on the sleeve 3 and which, as shown in Fig. 6, cooperates by means of a conical inner surface with locking balls 9 which are distributed round the circumference of said surface and are arranged in holes in the sleeve 3. The locking balls 9 can be forced against the thread guide carrier rod 1 by the locking sleeve 8, in such a manner, that this rod is connected with the sleeve 3 and thus with the thread guide 6 for common movement.

The conical feeler member 10, which, as shown in Fig. 8, is axially adjustable by means of screw 11 relative to a carrier sleeve 12, cooperates with the carrier arm 5 of the thread guide 6. The sleeve 12 which is provided at one end with an outer flange 13 carries at the other end an inner rim 14 being arranged in a bore of this sleeve and having an embossed peripheral surface, whilst a central portion of this sleeve has a threaded portion 15. The winding feeler member 10 is mounted by means of its carrier sleeve 12 on a guide spindle 16 having a threaded portion 17 which extends over a surface portion of the spindle 16 amounting to slightly less than half the circumferential length of this spindle. As shown in Figs. 8, 9, 12 and 13 the threaded portion 15 of the sleeve 12 is engaged with the threaded portion 17 of the guide spindle 16. The spindle 16 is received at one end in the mounting member 2 and at the other in a mounting arm 18, as shown in Figs. 9 to 13, which arm is connected with the gear box 35 by means of a supporting bar 40. The mounting member has secured thereto a bushing 19 which receives the guide spindle 16 and is provided with a helical change-over slot guide 20 extending over half the circumference of the bushing and engaging with a screw stud 21 secured crosswise to the guide spindle 16 so as to function as a guide piece for the latter. On the spindle 16 are further secured two adjustable stop members 22, 23, the member 23 being in the form of a set collar. The member 22 may also be constituted by a set collar if

desired. The coaction of the pin 21 with the slot guide 20 of the stationary boss 19 serves to cause rotation of the guide spindle 16 about its own axis when this spindle is moved axially. Axial movement of the guide spindle 16 (to the right and thereafter to the left) is effected by means of the stops 22, 23 provided on it since the carrier sleeve 12 or the feeler 10 strikes against the stop 22 and later (on its return) against the stop 23, thus each time exerting a corresponding axial thrust on the guide spindle 16.

A slide 25 is displaceably arranged on a rod 24 and carries, by means of a screw stud 26, a pivotal catch 27 which is provided within the extent of its hub portion with a downwardly directed nose 28. A stop pin 29 secured to the slide 25 limits the range of rocking movement of the pivotal catch 27. The catch 27 is adapted for cooperation with a pin 30 which is arranged on a projection of the carrier arm 5 of the thread guide 6. As shown in Figs. 1 and 2, a connecting piece 41 is provided which is connected with a control arm 44 by means of a rod 42 and another connecting piece 43, the arm 44 being fastened to a shaft 45 which can be coupled to the driving gearing within the gear box 35.

A number of spools 31 are carried by spool holders or driving heads 46 mounted in common, in a manner known per se, by means of spindles, on a revolvable supporting member 47 which is fed through a part-turn each time after a spool has been wound by means of a feed device located within the box 35, whereby each time an empty spool 31 is moved into the working or winding position at which the respective driving head 46 is coupled to the driving spindle of the machine (Fig. 2).

At the beginning of the winding operation the winding feeler member 10 and the thread guide 6 are in their initial positions as shown in Figs. 12 and 13. The slide 25 is in its position of rest. By the movement of the cam member 36 the rod 1 is actuated and the thread guide 6 is accordingly reciprocated whereby the initial portion of a winding 32 is formed by the thread on the spool 31 being located at the working position. During the winding, the rod 1 is reciprocated axially, causing the support arm 5 and the thread guide 6 to be correspondingly reciprocated and the thread to become wound up on the reeling member 31. The reel of thread 32 then comes in contact with the feeler cone 10 which rotates as a result of the friction produced and therefore moves forward along the screw-threaded part 17 of the guide spindle 16. The winding feeler 10, as it moves along, bumps into the projection 5' of the carrier arm 5 with the result that the axial thrust produced on the parts 3, 9 of the locking sleeve causes the latter to become released and moved one step forward on rod 1. The spring 1 causes the bushing 8 to follow the parts 3, 9, whereupon the locking sleeve again rigidly engages the rod 1. This produces the step-wise, intermittent, movement of the locking sleeve and hence of the thread guide 6 on the rod 1. This intermittent feeding of the thread guide 6 requires the resistance of the compression spring 7 abutting on the locking sleeve 8 (Figs. 6 and 9) to be overcome, so that the clamping mechanism constituted by the sleeve 3, the locking balls 9 and the locking sleeve 8 is displaced for a small feed step, whereupon this mechanism holds the thread guide 6 on the termination of the feed step in the new relative position of this guide to the rod 1.

The carrier arm 5 of the thread guide 6 slides during its reciprocating movement on the sleeve 12 of the winding feeler member 10. When the winding on the spool has almost reached the required length and the winding feeler member 10 is thus located near the end of its traverse, the slide 25 is advanced, that is, displaced in the direction away from the gear box 35, by the shaft 45 having been automatically coupled to the driving gearing and performing only one revolution. In the course of this movement a projection 49 provided on the slide 25 (Figs. 9 and 13) meets with the pin 30 arranged on the carrier arm 5 of the thread guide 6, in consequence whereof the arm 5 then moves in unison with the slide 25. The carrier arm 5 in turn hits the flange 13 on the sleeve 12 of the feeler means, whereupon this sleeve is also moved along by the slide 25. Since the feed movement of the sleeve will already have brought flange 13 into contact with stop member 22, the latter has pressure exerted on it by flange 13 which presses spindle 16 to the left so that guide slot 20 and stud 21 function to turn spindle 16 as previously explained to bring spindle 16 into such position that threads 17 and 15 are out of engagement and sleeve 12 is free to slide in spindle 16, thereby hitting the stop member 22 on the guide spindle 16.

By influence of the resulting axial pressure effect on the guide spindle 16 the latter is turned for half a revolution by cooperation of the guide stud 21 on this spindle with the cam slot guide 20 in the stationary bushing 19. Consequently the threaded portion 15 of the sleeve 12 of the winding feeler means is moved out of engagement with the screw threads on the guide spindle 16 so that the feeding of the winding feeler member 10 is ceased. Thereupon, the member 10 then bearing on the circumferential portion of the guide spindle 16 devoid of screw threads is pulled back into initial position by sliding on this spindle. This is effected by the pivotal catch 27, having entered into engagement with the pin 30 on the carrier arm 5 during the advance movement of the slide 25, moving the arm 5 along during the return movement of the slide 25 following said advance movement. In the course of this operation the carrier arm 5 hits the winding feeler member 10 by means of a projection 5' (Fig. 12), due to which the thread feeler means is coupled to the arm 5 so as to move the feeler along with it. During the movement of the slide member 25 from its position of rest, the flange 13 of the carrier sleeve 12 has engaged against the adjusting ring 22 of the spindle 16. The slide member 25 then forces the support arm 5 of the thread guide 6 (which it has picked up en route) against the flange 13 of the adjusting ring or stop 22 so as to produce half rotation of the guide spindle 16, as previously explained. This disengages the screw-thread engagement of the carrier sleeve 12 so that it can be pulled back to the starting position when the member 25 returns.

In the course of the displacing movement of the slide 25 the revolvable supporting member 47 performs one rotational feed step for removing the fully wound spool from the working position and moving an empty spool into that position. As the slide 25 approaches the initial position the pivotal catch 27 hits a stud 33 with its nose 28, as shown in Fig. 12, whereby the catch 27 is rocked so as to release the pin 30. In the course of the return movement of the winding feeler member 10 the latter hits the stop member 23 of the guide spindle 16 so that this spindle is then

turned for half a revolution again by cooperation of the guide stud 21 with the cam slot guide 20 in the stationary bushing 19, whereby the guide spindle is returned into position of operation. In this connection the threaded portion 17 of the 5 guide spindle 16 enters again into engagement with the threaded portion 15 of the sleeve 12 of the feeler means so that operative connection between the guide spindle 16 and the winding feeler member 10 is re-established. In consequence of this the feed means provided by the winding feeler member 10 and the parts associated therewith is in condition for operation for beginning the winding of a new cop.

The spring disposed on rod 24 tends to keep the support of the winding member 31 against the winding member 31 in known manner. Upon termination of the winding procedure, the member 25, which has moved forward on the rod 24, serves to push back said support, against the 20 action of the aforesaid spring, causing the finished, reeled spool 32 to become released at the proper place and to drop off from the spool spindle or from the rotary head 41.

By adjusting the two stop members 22, 23 arranged on the guide spindle 16 of the winding feeler member 10 the time of the beginning of cooperation of these members with the winding feeler member can be controlled. Further control is possible due to the axial adjustability of 25 the winding feeler member relative to its carrier sleeve 12.

In the embodiment of the feed means described no stop frame is required for the winding feeler member. It is, however, obvious that the winding feeler member may, for example, also be in the form of a disc, in a manner known per se.

I claim:

1. In a machine for winding cops by means of thread material, in combination, thread guide means for cooperation with the cop winding, winding feeler means for feeding said thread guide means in dependence upon the cop building operation, a screw bore associated with said winding feeler means for intermittently feeding said feeler means, a rockable guide spindle provided with screw threads on only a part of its circumference, said screw threads operatively engaging with said screw bore in a normal rocking position of said spindle, a stop member on said spindle for cooperation with said winding feeler means for slidably returning said winding feeler means to its initial position of operation on the circumferential spindle portion devoid of screw threads with said spindle moved out of said normal rocking position, and a further stop member on said spindle for cooperation with said winding feeler means for rocking said spindle back into said normal position with said screw threads intermeshing.

2. In a machine for winding cops by means of thread material, in combination, thread guide means for cooperation with the cop winding, winding feeler means including a winding feeler member, for feeding said thread guide means in dependence upon the cop building operation, a sleeve having a screw bore associated with said winding feeler means and carrying said feeler member in axially adjustable relation thereto and serving for intermittently feeding said feeler member, a rockable guide spindle provided with screw threads on only a part of its circumference, said screw threads operatively engaging with said screw bore in a normal rocking position of said spindle, a stop member on said spindle for coop-

eration with said winding feeler means for slidably returning said winding feeler means to its initial position of operation on the circumferential spindle portion devoid of screw threads with said spindle moved out of said normal rocking position, and a further stop member on said spindle for cooperation with said winding feeler means for rocking said spindle back into said normal position with said screw threads intermeshing.

3. In a machine for winding cops by means of thread material, in combination, thread guide means for cooperation with the cop winding, winding feeler means for feeding said thread guide means in dependence upon the cop building operation and including a winding feeler member, a sleeve having a screw bore associated with said winding feeler means and carrying said feeler member in axially adjustable relation thereto and serving for intermittently feeding said feeler member, a rockable guide spindle provided with screw threads on only a part of its circumference, said screw threads operatively engaging with said screw bore in a normal rocking position of said spindle, a stop member on said spindle for cooperation with said sleeve for slidably returning said sleeve to its initial position of operation on the circumferential spindle portion devoid of screw threads with said spindle moved out of said normal rocking position, and a further stop member on said spindle for cooperation with said winding feeler means for rocking said spindle back into said normal position with said screw threads intermeshing.

4. In a machine for winding cops by means of thread material, in combination, thread guide means for cooperation with the cop winding, winding feeler means for feeding said thread guide means in dependence upon the cop building operation, a screw bore associated with said winding feeler means for intermittently feeding said feeler means, a rockable guide spindle provided with screw threads on only a part of its circumference, said screw threads operatively engaging with said screw bore in a normal rocking position of said spindle, a set collar providing an adjustable stop member arranged on said spindle for cooperation with said winding feeler means for slidably returning said winding feeler means on the circumferential spindle portion devoid of screw threads with said spindle moved out of said normal rocking position, and a further stop member on said spindle for cooperation with said winding feeler means for rocking said spindle back into said normal position with said screw threads intermeshing.

5. In a machine for winding cops by means of thread material, in combination, thread guide means for cooperation with the cop winding, winding feeler means for feeding said thread guide means in dependence upon the cop building operation, a screw bore associated with said winding feeler means for intermittently feeding said feeler means, a rockable guide spindle provided with screw threads on only a part of its circumference, said screw threads operatively engaging with said screw bore in a normal rocking position of said spindle, a guide piece arranged on said spindle for rocking the latter into and out of said predetermined rocking position in accordance with a stationary change-over cam track, a stop member arranged on said spindle for cooperation with said winding feeler means for slidably returning said winding feeler means to its initial position of operation on the

circumferential spindle portion devoid of screw threads with said spindle moved out of said normal rocking position, and a further stop member on said spindle for cooperation with said winding feeler means for rocking said spindle back into said normal position with said screw threads intermeshing.

6. In a machine for winding cops by means of thread material, in combination, thread guide means for cooperation with the cop winding, winding feeler means for feeding said thread guide means in dependence upon the cop building operation, a screw bore associated with said winding feeler means for intermittently feeding said feeler means, a rockable guide spindle provided with screw threads on only a part of its circumference, said screw threads operatively engaging with said screw bore in a normal rocking position of said spindle, a guide piece arranged on said spindle for rocking the latter into and out of said predetermined rocking position, a stationary sleeve receiving said guide spindle and having a circumferential change-over cam slot for accordingly guiding said guide piece, a stop member arranged on said spindle for cooperation with said winding feeler means for slidably returning said winding feeler means to its initial position of operation on the circumferential spindle portion devoid of screw threads with said spindle moved out of said normal rocking position, and a further stop member on said spindle for cooperation with said winding feeler

means for rocking said spindle back into said normal position with said screw threads intermeshing.

7. In a machine for winding cops by means of thread material, in combination, thread guide means for cooperation with the cop winding, winding feeler means for feeding said thread guide means in dependence upon the cop building operation, a screw bore associated with said winding feeler means for intermittently feeding said feeler means, a slide associated with said thread guide means for returning the latter into initial position of operation, means for coupling said winding feeler means with said thread guide means for the former to be moved along by the latter during said return movement into its initial position of operation, a rockable guide spindle provided with screw threads on only a part of its circumference, said screw threads operatively engaging with said screw bore in a normal rocking position of said spindle, a stop member arranged on said spindle for cooperation with said winding feeler means for slidably returning said winding feeler means to its initial position of operation on said circumferential spindle portion devoid of screw threads with said spindle moved out of said normal rocking position, and a further stop member on said spindle for rocking said spindle back into said normal position with said screw threads intermeshing.

WALTER SIEGENTHALER.
